UNITED STATES PATENT OFFICE.

THOMAS JOHN WOODWARD, OF WEST BROMWICH, ENGLAND, ASSIGNOR TO
CHANCE BROTHERS & CO., LIMITED, OF WEST SMETHWICK, ENGLAND.

DESIGN FOR ORNAMENTATION OF PLATE-GLASS.

SPECIFICATION forming part of Design No. 26,939, dated April 20, 1897.

Application filed March 3, 1897. Serial No. 625,899. Term of patent 14 years.

To all whom it may concern:

Be it known that I, THOMAS JOHN WOODWARD, designer, a subject of the Queen of Great Britain, residing at Beeches' Road, 5 West Bromwich, England, have invented and produced a new and original Design for the Ornamentation of Plate-Glass, of which the following is a specification, reference being had to the accompanying drawing, forming 10 part thereof.

The drawing represents the face of a piece of plate-glass ornamented with my design and also a cross-section of the same, taken on the line $x-x$.

15 The design is composed of a series of curved or flowing stems or lines $a-a-a$, resembling tracery or veins, from which spring prismatic

fir-tree cones $b-b-b$, the whole being arranged on a pyramidal ground c , the said ground being in low relief, as will be seen by reference to the section, so as not to interfere with the flowing lines or stems $a-a-a$ and fir-tree cones $b-b-b$, which constitute the characteristic feature of the design. 20

What I claim is—

25 The design for plate-glass substantially as herein shown and described.

In testimony whereof I have affixed my signature in presence of two witnesses.

THOMAS JOHN WOODWARD. [I. S.]

Witnesses:

RICHARD SKERRETT,
ARTHUR JOHN POWELL.
